C. & C. Co. No. 1000

Canada Patent

Oct. 11, 1866

Letters Patent.

The inventor wishes to inform these Letters Patent and making part of the same containing a description in the words of the inventor himself of his improvement in the Steam Engine.

First in a piston moving in a circular cylinder or steam chest, instead of reciprocating in a vertical one by which means the power is applied immediately to the main axis; second the power acts constantly at right angles which can not be the case in the common engine.

Third the steam act without intermission on the piston constantly propelling it forward whereas in the common engine the piston is brought to rest twice in every revolution of the main axis.

My engine is constructed upon the following manner. The cylinder or steam chest may internally contain a boiler, or the common cylinder lying horizontally. The axis passes through its center; the piston is attached to the axis. As the axis revolves the piston describes a circle corresponding to the internal cavity of cylinder. To prevent the steam from passing by the piston it is packed after the common manner. Opposite sides of the cylinder are two sliding valves for the steam alternately to meet upon. If one of these valves be shut, and the piston standing in front of it the steam be admitted between them it will of necessity act on the piston, and prop it forward; the opposite valve being open the piston will pass its place in the cylinder without obstruction, but immediately on the piston passing that point the valve begins to close and will be completely shut when the piston has gone to a right

from a right angle with it, at the instant the steam is forced into the other part of the cylinder between the piston and the valve that has just closed, while the steam behind this valve is condensed, and the other sliding valve is opened so that the piston now passes by its place in the cylinder, and has the use of the other when this valve also closes the steam is shifted as before between the valve and piston and the opposite side at the same time is condensed.

Since then the sliding valve in the cylinder which opens at the approach of the piston and closes after it shuts steam in the middle of the steam it is evident that at the moment the steam shifts it is in the act of shifting that section of the cylinder which lies between the valve last shut and the piston is fully charged with steam into which the steam is again admitted as it shifts which is an operation almost instantaneous, hence the piston must have the full and constant action of the steam upon it and a constant vacuum before it, if the steam be shifted by the hand of the engineer so as to act on the opposite side of the piston, the motion is instantly reversed, which will continue until by a similar operation the first piston be again restored. It may be proper here to state that I make use of the common condensing apparatus, only adapting it to my engine, and also that convey the steam into the cylinder through the common steam chest, & shift it by the sliding valve therein.

With these exceptions, the above described engine I claim as an invention and improvement of my own.
